(57) **CLAIM**

The ornamental design for a RV electrical adapter, as shown and described.

DESCRIPTION

FIG. 1 is a perspective view of a RV electrical adapter showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof, shown enlarged in scale;

FIG. 7 is a bottom plan view thereof, shown enlarged in scale;

FIG. 8 is an enlarged detail view of the encircled area 8, shown in FIG. 5; and,

FIG. 9 is another enlarged detail view of the encircled area 9, shown in FIG. 5.

The broken lines shown in the drawings illustrate portions of the RV electrical adapter that form no part of the claimed design. The broken lines encircling the detail portions in FIGS. 5, 8, and 9 illustrate the boundaries of the detail portions, and form no part of the claimed design.
